(57) **CLAIM**

I claim, the ornamental design for an earplug, as shown and described.

DESCRIPTION

FIG. 1 is a perspective view of an earplug, showing my new design,

FIG. 2 is a first side elevation view thereof, the opposite side being a mirror image thereof;

FIG. 3 is a second side elevation view thereof, the opposite side being a mirror image thereof;

FIG. 4 is a top plan view thereof; and,

FIG. 5 is a bottom plan view thereof.

The broken lines in FIGS. 1, 2, 3, 4, and 5 represent environmental matter and form no part of the claimed design. The surface shading is provided only to indicate contour.
